LIQUID-EJECTING APPARATUS

Floyd J. Lee, La Habra, Calif., assignor of one-half to J. Leonard Hull, Los Angeles, Calif.

Application May 13, 1944, Serial No. 535,446

8 Claims. (Cl. 169—31)

This invention relates to a liquid-ejecting apparatus, such for example as those used in expelling the contents of a fire extinguisher. Heretofore the means employed for expelling the contents of a fire extinguisher have been greatly affected by temperature.

A common method of expelling the contents of fire extinguishers has been by the reaction of chemicals to produce a gas such as carbon dioxide. The reaction rate of such chemicals is so affected by temperature that the extinguishers are not usable except under particular temperature conditions. Various other means, such as the release of condensed gases in the fire extinguishers, have been employed for expelling the contents thereof, but such means are likewise subject to wide fluctuations under temperature conditions, and in particular may utterly fail in cold temperatures.

It is the general object of the present invention to provide a means for ejecting the contents of a fire extinguisher or other apparatus, which means is substantially unaffected by temperature.

Another object of the present invention is to provide an ejecting means for liquid which in addition to being unaffected by temperature includes means for initiating its action which means are entirely enclosed within the apparatus and are automatically responsive to an inversion of the apparatus for initiating the liquid-ejecting operation.

The liquid-ejecting apparatus of the present invention operates by the generation of gases through burning of powder trains. Previous to the present invention it has been suggested to employ powder in the form of a cartridge as a means for generating gases for ejecting liquids from apparatus, the cartridge being ignited by a striking pin actuated by trigger mechanism extending to the exterior of the apparatus. These prior devices are unsatisfactory in that the cartridges on being ignited fire so rapidly as to generate a large and excessive pressure at instigation of the operation of the devices, which is dangerous to the operator. The pressure in the devices is rapidly built up to over a satisfactory limit and thereafter, as the contents of the apparatus are expelled, the pressure decreases, the result being that if the cartridges employed are sufficiently restricted in size to allow for safe operation of the device at the starting time, the pressure decreases so rapidly that it is insufficient for proper ejection of the liquid. If sufficient powder is employed to insure sufficient gas pressure to fully eject the contents of the apparatus,

then a dangerous pressure exists at the igniting time. The burning time of powder cartridges not only varies with the pressure on the cartridges but also varies with the past history of the cartridge. Cold temperature may cause the separation of powder in a cartridge and the formation of channels through the cartridge with the result that the firing time of the cartridge is very greatly accelerated.

These disadvantages of prior apparatus using powder as a fluid-ejecting means, are eliminated in the apparatus of the present invention through the use of the burning substance or powder in the form of a multiplicity of separate powder trains or fuses. By supplying the powder which on ignition is to form the ejecting gas in the form of slow-burning fuses, I am able to continue the gas generating period substantially throughout the period of time used for ejecting the liquid from the apparatus. As a result I avoid the creation of excessive pressures at the instigation of the operation and maintain a more uniform pressure of gases for expelling the liquid throughout the period of liquid ejection.

Moreover through the employment of a multiplicity of powder trains or fuses I have found that the action of the apparatus is substantially unaffected by temperature. There is no appreciable mass of powder present in any one train or fuse capable of being affected by temperature change so as to separate or channel. The firing time of the powder trains therefore remains substantially unaffected by their previous exposure to temperature changes or to the temperature of the apparatus at the time of operation.

The present invention also includes a trigger actuating means for firing or igniting the powder trains which is entirely enclosed within the housing of the apparatus and includes a weight releasing means for actuating the trigger on inversion of the apparatus to predetermined position, the weight releasing means including the time-delay action in order to lessen the chance of instigation of operation by accidental inversion.

This invention, together with other objects and advantages of the invention, will be fully understood from the following description of a preferred form or example of a fire extinguishing apparatus embodying the invention. I have, therefore, described the preferred example of the invention in connection with the accompanying drawing, in which

Figure 1 is an elevation, mainly in vertical section;

Figure 2 is a section on the line 2—2 of Fig. 1, omitting the extinguisher body;

Figure 3 is an enlarged fragmentary section of the primer; and

Figure 4 is a section on the line 4—4 of Fig. 3.

One feature of the present invention is that the liquid-ejecting apparatus is so designed as to be a complete independent unit and as such capable of being substituted in fire extinguisher bodies now in use for replacing any liquid-expelling apparatus previously used therewith. No operating means which extend outside of the extinguisher are required. Thus as illustrated in the accompanying drawing, 2 is any usual or conventional form of extinguisher body (or other liquid holder from which the contents are to be ejected). The extinguisher 2 is indicated as having the usual outlet 3 by which it may be attached to a delivery hose, not shown. The body 2 is provided with any usual or preferred cap 4 threaded as indicated at 5 to the neck of the body.

The apparatus of the present invention includes a mounting member 6 into which are threaded a number of mounting pins 7, preferably pointed at their ends, by means of which the apparatus may be suspended from the neck of the extinguisher body 2. Three or more of the adjustable pins 7 are provided for affording the suspension mounting. The mounting member 6 is provided with a recess 8 in which is pivotally mounted a firing lever or trigger 9. The firing lever 9 is pivoted on an extension of the disc 6a which closes the bottom of the mounting member 6.

The firing lever 9 is provided with a firing pin positioned for striking a priming cap 10. The priming cap 10 is mounted on a plug 11 of a tube 12. Below the plug 11 is provided a disc 30, made of any suitable material, such as paper, adapted to be burned out. Below the disc 30 is provided a cap 29 having two openings therethrough, one for the fuse 13 and the other serving as a gas discharge opening. The opening through the cap 29 registers with similar openings through the plug 11. Below the cap 29 is a short sleeve 28 into which there is extended the ends of a bundle of firing trains or fuses 15 held within the tube 12. The upper end of the fuses 15 terminate slightly below the cap 29 and the intervening space is filled with a supply of powder 14 which serves as a priming charge for igniting each of the fuses 15. The fuses 15 extend to substantially the bottom of the tube 12. The tube 12 is attached at its upper end to the disc 6a and is provided with a closure cap 16 at its lower end.

The fuses or powder trains 15 may be constructed in various manners, the essential need apparently being that the powder to be ignited should be separated into a multiplicity of trains of powder maintained separately from each other. For example, I have employed ordinary fusing material which contains a small core of powder wrapped in jute having an asphalt coating.

These fuses are assembled in a bundle, as indicated, and for holding them in this position they may be tied at a plurality of points along the length of the fuse, as indicated by the cord 17. Each individual fuse 15 extends substantially the entire length of the tube 12, and each individual tube is preferably of the type designed to consume approximately 55 seconds in burning from end to end.

The mechanism for actuating the trigger 9 comprises a guide tube 18 secured to the disc 6a at one end and extending parallel to the tube 12. A cross-over connection 19 is provided for pressure equalizing under firing conditions between tubes 18 and 12. At the lower end of the tube 18 when the apparatus is in the position as viewed in Figure 1, is provided a weight 20 which is generally cylindrical in form. A lead weight is preferable and the diameter of the weight 20 should have a free fit with the bore of the tube 18 so as to be capable of falling freely and rapidly through the tube 18 when the apparatus is inverted and the weight released, as hereafter described.

The diameter of the weight 20 should however conform fairly closely to that of the bore through the tube 18 for reasons hereinafter pointed out. The lower end of the weight 20, as viewed in Fig. 1, is provided with a recess and across the recess is provided a rod or wire 21. A cap 22 is threaded to the lower end of the tube 18 and from the base of the cap there extends a helically curved or corkscrew-shaped wire 23 which contacts the wire 21 so as to prevent axial movement of the weight 20, except as the weight 20 rotates in accordance with the pitch of the wire 23.

The wire 23 and the wire 21 constitute a time-delay means for retarding the fall of the weight 20 through the tube 18 when the apparatus is inverted. By providing a fairly close although free running space between the weight 20 and the tube 18 the apparatus must be inverted to within a few degrees of the true vertical position before the friction between the sides of the weight and tube is reduced to the point where the weight 20 may be rotated to untangle itself from the wire 23. When the apparatus is inverted there is a short interval of time during which the weight is rotated to release itself from wire 23 before the weight falls through the tube 18. In this way I protect the operator of the apparatus from accidental discharge of the apparatus which might otherwise occur merely by a momentary inversion of the apparatus.

When the apparatus is inverted and the weight 20 released, it falls until it strikes the pivotally mounted firing lever 9, instigating the operation of the apparatus.

The mounting member 6 is indicated as having an opening closed by a plug 25. The plug 25 is designed so that when it is desired to ship the apparatus the plug 25 may be removed and a suitable means, such as a wire (not shown), may be inserted for contacting the weight 20 to hold it in position when shipping the apparatus. The contents of the tube 12 are obviously completely sealed off from the liquid contained within the extinguisher body 2.

A blow-out port is provided, closed by a blow-out seal 27. This blow-out seal 27 is preferably designed to blow-out on the generation of about 10 pounds of gas pressure in the ejector apparatus and such amount of pressure is approximately that produced on burning the powder 14 which ignites the powder trains 15. When the seal 27 is blown out gas pressure is admitted into the body 2.

The apparatus of the present invention is found to be reliably operative under a wide range of temperature, including temperatures so low that anti-freeze materials are necessary to prevent freezing of the liquid contents of the extinguisher body 2.

While the particular form of the apparatus herein described is well adapted for carrying out the objects of the present invention, it is to be understood that the apparatus is capable of a number of modifications and changes, and this invention is not limited to the particular form shown, but includes all such modifications and changes as come within the scope of the appended claims.

I claim:

1. A liquid-ejecting apparatus, comprising a body member for containing a liquid, a combustion chamber mounted within said body member, a plurality of powder trains within said combustion chamber adapted to produce a gas on slow burning, means for igniting said powder trains, communication means between said combustion chamber and said body member and a blow-out seal in said communication means.

2. A liquid-ejecting apparatus, comprising a body for the liquid to be ejected, a gas generating means positioned within said container, said gas generating means comprising a combustion chamber, a plurality of separate powder trains mounted in said combustion chamber, and means for simultaneously igniting said powder trains.

3. A gas generating unit for a liquid-expelling apparatus, which comprises a combustion chamber, a plurality of parallel fuses positioned in said combustion chamber, a primer, and means for substantially simultaneously igniting one end of said fuses on ignition of said primer.

4. A gas generating unit for a liquid expelling apparatus, including a mounting member for mounting the unit inside of the liquid holding compartment of the liquid expelling apparatus, said mounting member being connected to a combustion chamber, a plurality of parallel separate powder trains mounted in said combustion chamber, and firing means for simultaneously igniting one end of each of said powder trains.

5. A gas generating unit for a liquid expelling

apparatus, including a mounting member for mounting the unit inside of the liquid holding compartment of the liquid expelling apparatus, said mounting member being connected to a combustion chamber, a plurality of parallel separate powder trains mounted in said combustion chamber, wiring means for simultaneously igniting one end of each of said powder trains, said firing means including a firing trigger, a weight, and weight-guiding means operative on inversion of the unit.

6. A liquid-ejecting apparatus comprising, a body for containing a liquid to be ejected, a combustion chamber mounted within said body, a plurality of parallel separate powder trains within said combustion chamber, firing means for simultaneously igniting one end of said powder trains, said firing means including a trigger, a weight movable to strike said trigger, and a time-delay release for said weight.

7. A unit adapted for installation entirely within a fire extinguisher body, said unit including a mounting member having means for supporting the unit from the neck of the extinguisher body, a combustion chamber connected to said mounting member and having a plurality of parallel separate powder trains, means for substantially simultaneously igniting each of said powder trains, including a trigger, weight-actuating means for said trigger, and a time-delay release for said weight.

8. A wire extinguisher comprising an extinguisher body for holding a liquid to be expelled, a gas generating unit for expelling the liquid from said body, mounted entirely within the body, said gas generating unit comprising a combustion chamber mounting a plurality of separate powder trains, including a trigger means for substantially simultaneously igniting said powder trains, and means operative on inversion of the unit for automatically actuating said trigger.

FLOYD J. LEE.
